UNITED STATES PATENT OFFICE.

MORRIS WOLF, OF NEW YORK, N. Y.

DESIGN FOR A SIFTER-TOP RECEPTACLE.

58,654.

Specification for Design.

Patented Aug. 2, 1921.

Application filed December 2, 1920. Serial No. 427,910. Term of patent 3½ years.

To all whom it may concern:

Be it known that I, MORRIS WOLF, a citizen of the United States, and a resident of the city of New York, borough of the Bronx, in the county of Bronx and State of New York, United States of America, have invented a new, original, and ornamental Design for a Sifter-Top Receptacle, of which the following is a specification, reference

being had to the accompanying drawing, forming part thereof.

Figure 1 is a perspective of the sifter top receptacle.

Fig. 2 is a bottom view thereof.

I claim:

The ornamental design for a sifter top receptacle, as shown.

MORRIS WOLF.
